[57] CLAIM

The ornamental design for a mirror, as shown and described.

DESCRIPTION

FIG. 1 is a front perspective view of a mirror showing my new design, the undisclosed rear is plane and unornamented;

FIG. 2 is a front elevational view thereof;

FIG. 3 is a top plan view thereof;

FIG. 4 is a bottom plan view thereof; and,

FIG. 5 is a side elevation view thereof, the side opposite is a mirror image of the side shown.
